PROCESS AND APPARATUS FOR MIXING GASES.

1,378,429.

Specification of Letters Patent. Patented May 17, 1921.

Application filed February 5, 1918. Serial No. 215,562.

To all whom it may concern:

Be it known that I, FREDERICK A. STAMPS, a subject of the Kingdom of Great Britain, and a resident of Niagara Falls, New York, have invented a new and useful Improvement in Processes and Apparatus for Mixing Gases, which invention is fully set forth in the following specification.

This invention relates to the mixing of two or more gaseous bodies or "gases" in predetermined relative amounts; and the object of the invention is to insure the maintenance of the proper proportions of the respective gases. In carrying out the invention with only two gases, one gas is delivered through an uncontrolled supply-pipe, while the other gas is delivered through a separate supply-pipe which is controlled, as by a valve; and any variation of the gas-flow through the uncontrolled pipe is caused to produce a corresponding variation of flow through the other pipe, as by acting upon its valve. In case three (or more) gases are to be mixed, there will be two (or more) separate operations, *e. g.*—two of the gases will first be mixed in their proper proportions, and to this mixture the third gas (or a similarly-proportioned mixture of gases) will in like manner be added in the predetermined proportion.

Broadly stated, the invention comprises, among other things, the process of delivering two gases in separate confined columns of flow, and causing the variation of pressure attending a variation of flow of one column to produce a corresponding variation of flow of the other column; and also the process of counter-balancing the gas-pressure of the two separate confined columns, and causing a relative variation of such counter-pressure to maintain the predetermined proportion of flow of the two columns. The invention further comprises suitable mechanism for carrying out the foregoing operations. More specifically the invention comprises also the combination of two separate supply-pipes, a valve controlling one of them, a float-device acted upon by the gas-pressure in the two pipes, and suitable means actuated by the relative movement of said float-device and thereupon operating said valve. The invention consists further of the various features herein-after set forth and claimed.

The new process may be varied in its details, and may be carried out by means of various different structures; but, for the sake of clearness, the annexed drawings show and the following specification sets forth, though merely by way of illustration, certain preferred physical embodiments of the new apparatus suitable for carrying out the new process. However, it will be understood that the same are merely illustrative of the spirit of the invention, and that the invention is nowise limited to the precise details hereinbelow set forth.

In the annexed drawings, Figure 1 is an elevation, indicating diagrammatically one preferred apparatus or general arrangement of parts employed in carrying out the invention;

Fig. 2 shows, on a larger scale, a vertical section through the preferred embodiment of the operative parts;

Fig. 3 is a plan of a preferred arrangement of connections for actuating the proportioning-valve;

Fig. 4 is a vertical section through the proportioning-tank, showing certain modifications; and

Fig. 5 is a modified arrangement for actuating the valve.

The two supply-pipes 1 and 2 lead separately from the independent sources of supply of their respective gases. One of these pipes, as 1, is provided with a suitable valve 3, hereinafter designated the proportioning-valve, being preferably a valve operable through a considerable range from its entirely-closed to its fully-opened position. At their ends the two supply-pipes are shown as converging into a single discharge-outlet 4, to lead into a common receptacle, such as 5. But, if desired, the two pipes might of course have independent outlets, as indicated by dotted lines.

The proportioning-mechanism comprises the hermetically-enclosed tank 6, located between the two supply-pipes and divided into two compartments by the vertical partition 7, tightly joined at the top and sides and extending not quite to the floor of the tank. Within the tank is a body of suitable liquid 8, such as oil, whose surface occupies a level a sufficient distance above the lower end of said partition to constitute a liquid seal between the two compartments. Be-

neath said partition, and parallel with it, is the horizontal rock-shaft 9, journaled in suitable stuffing-glands in the sides of the tank, and carrying upon one protruding end 5 the external upright shift-rod 10 (for actuating the proportioning-valve 3, as herein-after explained). This shift-rod is angularly adjustable upon the rock-bar, but is clamped rigidly in the selected position of 10 adjustment. A lever 11, located within the tank at right angles to this rock-shaft, is rigidly secured upon the middle of said shaft; and to each end of said lever is connected a float,—the float 12 being buoyed 15 up by the liquid in one compartment, and the float 13 being buoyed up in the other. Preferably, the two arms of said lever are of equal length, and the two floats of equal area and of equal inherent buoyancy, so that 20 normally the two floats and their lever-arms are in horizontal equilibrium, while the upright shift-rod 10 will have been adjusted into true vertical position as its neutral position. Suitable pressure-communication is 25 provided between each supply-pipe and its own tank-compartment. In Fig. 2 this is shown as a small "Pitot tube" 14 leading from supply-pipe 1 into the compartment containing float 12, and a similar "Pitot 30 tube" 15 leading from supply-pipe 2 into the compartment of float 13, the inlet of each "Pitot tube" facing directly toward the oncoming current or column of gas in its supply-pipe.

35 The operation of the foregoing parts is obvious: The parts are so proportioned as normally to permit the passage, through supply-pipe 1, of just the desired volume of its gas in proportion to the volume of the 40 other gas normally passing through the other supply-pipe; and, if necessary, the shift-rod will then be adjusted upon the rock-shaft to occupy its neutral (preferably, vertical) position, and clamped in 45 such adjustment. Thereafter, in case a relatively too-great (or a relatively too-small) volume of either gas starts to pass through its supply-pipe (owing to variation of its pressure, or for other cause), thereupon the 50 attendant variation of pressure is transmitted through the bore of its "Pitot tube" and manifests itself by displacing the horizontal equilibrium of the floats, thereby swinging the shift-rod 10, which in turn 55 actuates the proportioning-valve 3 (by any suitable connection, such as the mechanical or electrical devices hereinafter set forth), to vary the amount of flow past that valve.

For instance, excess of flow of the gas 60 through supply-pipe 2, is attended at once by corresponding increase of pressure upon its float 13, and (the opposing pressure upon the other float being, as yet, unaltered) the equilibrium is destroyed and float 13 forced downward (float 12 rising); this actuates

the rock-bar and swings the shift-rod 10 to the right; and that movement in turn (through suitable connections) actuates proportioning-valve 3 in the direction to open a larger passage through its pipe 1, thus 70 reintroducing the proper proportion of the gases, and at the same time restoring the equilibrium of the floats and returning the shift-rod to its neutral position. Vice versa, 75 too small a flow of the gas through said supply-pipe 2, results in a decrease of the pressure upon its float 13, so that the as-yet unaltered pressure upon the other float 12 forces the latter down (lifting float 13); the shift-rod is thereby swung to the left, 80 and the proportioning-valve 3 is thereby actuated in the direction to reduce the flow of its gas,—thus again maintaining the proper proportions of the gases, and there- 85 with restoring the equilibrium of the floats and returning the shift-rod to neutral position.

A change of temperature of one of the gases, while the temperature of the other remains unchanged, would produce a corresponding change in the proportions of the two volumes being delivered. To avoid this, it is preferable to pass the two gases through a temperature-equalizer before they 90 reach the proportioning-device. As shown, 95 this comprises a water-jacket 16, inclosing the juxtaposed portions of the two supply-pipes, each of which may here consist of a coil.

It is also desirable to have an independent hand-actuated valve for each supply-pipe, for varying the total quantity of flow through the supply-pipes, or to cause the total cessation of flow of either gas. Such hand-valves may be located either between 100 the temperature-equalizer and the proportioning-device, as at 17, or in advance of 105 both, as at 18.

Any suitable connection may be employed 110 between shift-rod 10 and the proportioning-valve 3. But Figs. 2 and 3 show a preferred arrangement, comprising a horizontal journal 19, located parallel to and above the partition 7 and the rock-shaft 9, and supported at one end by being journaled in 115 the upper end of the shift-rod 10, while its other end is connected, as by a universal-coupling 20, to a suitable one-direction motor, as 21; and on said continually-rotating journal 19 is rigidly carried a driving-member, as cone 22. A horizontal shaft 23 is suitably supported to extend transversely of 120 said driving-journal 19; and near one end of said transverse shaft are secured two drivable members, as cones 24 and 25, one 125 on each side of said driving-cone, which they face; while the other end of said shaft 23 is connected to the screw-threaded stem of the proportioning-valve 3, as by a suitable train of reducing-gears conventionally 130

indicated at 26. When in its neutral position, the driving-cone 22 lies midway between the two cones 24 and 25, and out of contact with either (preferably only about, 5 say, $\frac{1}{4}$ of an inch from each); but when the floats shift the rod 10 to either side, the slight resultant lateral shift of the driving-cone is sufficient to bring it into frictional engagement with the drivable-cone on that 10 side, and thereby to rotate the valve-actuating shaft 23 in one direction or the other (according to the direction of the shift).

Thus, excess of flow through supply-pipe 2, depressing float 13, shifts the bar 10 to 15 the right, bringing cone 22 into engagement with cone 25; and the motor 21 is rotating in such direction as thereupon to rotate shaft 23 in such direction as to unscrew the stem of proportioning-valve 3,—thereby 20 opening a larger passage for the flow of gas through supply-pipe 1. And, on the other hand, a lessening of flow of gas through pipe 2, by shifting bar 10 to the left, brings cone 22 into operative engagement with the 25 other driving-cone, 24,—thereby rotating said shaft 23 in the opposite direction, thus screwing-down the valve-stem, and reducing the flow of the other gas (through pipe 1).

Fig. 4 shows a modification, in which a 30 compound expedient, consisting of a direct connection and a checking-device, is employed in place of the "Pitot tube" (a single expedient). That is to say, a simple tube 27 (27') leads at an angle from each 35 supply-pipe to its own tank-compartment, and farther on in the supply-pipe is located a choker or pressure-producing device, which preferably consists of a (comparatively thin) diaphragm as 28, having an aperture of carefully-predetermined area bearing the desired proportion to the area of the aperture in the corresponding choker in advance of the tube leading from the other supply-pipe. Such restricted passageway 40 through the pipe causes a back-pressure 45 which is transmitted through the tube 27 (27') to act upon the float and the surface of the fluid in its compartment. However, if desired, the choking-device may consist 50 of a short length of piping, as 29, fitted into the supply-pipe, and (as with the diaphragm) having the cross-sectional area of its bore carefully predetermined. But the length of the bore of such piping causes 55 friction, which varies with the speed (and density) of the current of gas passing through, and thus introduces another variable factor. Therefore, the apertured diaphragm is preferable to the piping.

60 Although the specific principle of back-pressure (as utilized when the simple tube and the choking-device are employed) may differ somewhat from the principle of impact-pressure (utilized when the "Pitot tube" alone is used), nevertheless the gen-

eral behavior of the modification of Fig. 4, and the ultimate results thereby produced, are substantially like those of Fig. 2; therefore further explanation is deemed unnecessary. However, the preferred arrangement 70 is that involving the "Pitot tube" structure in Fig. 2, which has been found more satisfactory in practice.

Fig. 5 indicates an electric control, in which the shift-rod 10' actuates an electric 75 switch 30, which, when shifted to one side, contacts with one set of electrical terminals of a suitable reversible electric motor 31, and when shifted to the other side contacts with another set of terminals to reverse said 80 motor. From the motor suitable connections, preferably with a slip-drive 32 interposed, serve to actuate the proportioning-valve, as through a worm and worm-gear 33.

The invention has thus been described in detail, but only for the sake of clearness, since the new process is not limited to any particular form or arrangement of apparatus; and some of the mechanical parts disclosed may be employed to the exclusion of other parts, and certain parts may be transposed or inverted or otherwise modified, without in any case departing from the 95 spirit of the invention.

The invention having been thus fully described in detail, what is claimed is:

1. The process in mixing two gases, which comprises causing each of the gases to flow under pressure in a separate column of fixed 100 cross-sectional area with a normal predetermined ratio between the velocities of flow of said gases in their respective columns, and causing a departure from said predetermined ratio to vary the velocity of flow of one of 105 said gases and thereby restore the said normal ratio of flow.

2. The process in mixing two gases, which comprises causing each of the gases to flow under pressure in a separate column of fixed 110 cross-sectional area with a normal predetermined ratio between the velocities of flow of said gases in their respective columns, and causing the flow of one of said gases to be governed by any change in the ratio of said 115 velocities of flow, whereby a substantially-constant ratio of flow is maintained.

3. The process of mixing two gases, which comprises causing each of the two gases to flow in a separate column of fixed cross-sectional area, the pressures of the two gases having a predetermined normal ratio, and bringing said pressures into opposition and thereby automatically controlling the flow of one of said gases in its column so as to 120 maintain such substantially-constant ratio between said pressures.

4. The process of mixing two gases, which comprises causing each of the two gases to flow in a separate column of fixed cross-sec- 125

tional area, the pressures of the two gases having a predetermined normal ratio and bringing said pressures into opposition, whereby upon the failure of said predetermined ratio the flow of one of said gases in its column is varied and said predetermined ratio of said pressures is restored.

5. The process, in mixing two gases, of maintaining the predetermined relative 10 amounts of the gases, which consists of delivering the gases in separate confined columns of predetermined normal flow of the proper relative proportions, and causing the variation in pressure attending a variation 15 in flow of one column to govern a source of power and thereby introduce a relay and thereby produce a proportionate variation in flow of the other column.

6. The process, in mixing two gases, of 20 maintaining the predetermined relative amounts of the gases, which consists of delivering the gases in separate confined columns of predetermined normal flow of the proper relative proportions, and causing a 25 variation of flow of one column to bring an external source of power into operation and thereby introduce a relay and thereby produce a proportionate variation of flow of the other column.

30 7. The process of mixing two gases, which consists of delivering one gas in a column of uncontrolled variability of flow, while delivering the other gas in a column of controllable flow, and causing a variation of 35 flow of the first column to introduce a source of power and thereby introduce a relay and thereby proportionately vary the flow of the second column.

8. The process of mixing two gases in any 40 desired proportions, which consists of separately supplying the gases in any predetermined ratio of flow, and causing a variation of flow of one column to introduce a source of power and thereby correspondingly vary 45 the flow of the other column so as to maintain the particular ratio selected, whatever that ratio may be.

9. An apparatus for mixing two gases in predetermined proportions, which comprises 50 the combination of two separate discharge-pipes, a valve controlling one of said pipes, an inclosed tank divided into two communicating compartments by a vertical partition, a pressure-communication between each of 55 said compartments and its own particular pipe aforesaid, a horizontal rock-shaft journaled in said tank beneath said partition, a lever adjustably secured upon said shaft, floats carried upon the ends of said lever and 60 located severally in said compartments, a body of liquid separating said compartments from each other and buoying up said floats, and suitable connections between said lever and said valve.

65 10. An apparatus for mixing two gases in

predetermined proportions, which comprises the combination of two separate discharge-pipes, a valve controlling one of said pipes, an inclosed tank divided into two communicating compartments by a vertical partition, a pressure-communication between each of 70 said compartments and its own particular pipe aforesaid, a horizontal rock-shaft journaled in said tank beneath said partition, a lever secured upon said shaft, floats carried upon the ends of said lever and located severally in said compartments, a body of liquid separating said compartments from each other and buoying up said floats, and suitable connections between said lever and said 80 valve.

11. An apparatus for mixing two gases in predetermined proportion, which comprises the combination of a discharge-pipe, a valve controlling said pipe and having a screw-threaded actuation, a revoluble shaft having operative connection with said valve and carrying two drivable members, a positively-rotated and laterally-swingable journal lying transversely of said shaft and carrying 85 a driving-member normally out of engagement with said drivable-members but movable into engagement with either of them by the lateral swing of said journal, a separate discharge-pipe, and means actuated by variation of flow through said second pipe to swing said journal.

12. An apparatus for mixing two gases in predetermined proportion, which comprises the combination of a discharge-pipe, a valve 100 controlling said pipe, a second discharge-pipe, an inclosed compartment partly filled with a body of liquid, a Pitot-tube connecting said second pipe and said compartment, a float buoyed up by said body of liquid, and 105 mechanism actuated by the rise and fall of said float to actuate said valve.

13. An apparatus for mixing two gases in predetermined proportion, which comprises the combination of two separate discharge-pipes, a valve controlling one of said pipes, means for applying in opposition to each other the respective gas-pressures from said pipes, means actuated by a relative variation of such counter-pressures, and means actuated by the last-named means and thereupon comprising a source of power actuating said valve.

14. An apparatus for mixing two gases in predetermined proportion, which comprises 120 the combination of two separate discharge-pipes, a valve controlling one of said pipes, two inclosed compartments each receiving the gas-pressure from its own pipe aforesaid, and a pressure-device comprising a 125 source of power subject to the action of said counter-pressures in said compartments and itself arranged to actuate said valve.

15. In an apparatus for mixing two gases in predetermined proportion, the combina- 130

tion of a plurality of separate fluid-circuits each adapted to deliver fluid in predetermined volume, proportioning-mechanism responsive to variations of flow in one of said circuits for maintaining a predetermined ratio between the respective flows in said circuits, and temperature-equalizing means

adapted to maintain the fluids in said circuits at substantially-constant temperatures to avoid disproportional changes in the volumes of the fluids delivered. 10

In testimony whereof I have signed this specification.

FREDERICK A. STAMPS.
